UNITED STATES PATENT OFFICE

124,940

DESIGN FOR AN EMBROIDERED COLLAR OR SIMILAR ARTICLE

August Ruesch, Woodcliff, N. J.

Application December 5, 1940, Serial No. 97,104

Term of patent 3½ years

To all whom it may concern:

Be it known that I, August Ruesch, a citizen of the United States, residing in Woodcliff, county of Hudson, State of New Jersey, have invented a new, original, and ornamental Design for an Embroidered Collar or Similar Article, of which the following is a specification, reference being had to the accompanying drawing, forming part thereof,

The figure of the drawing is a plan view of an embroidered collar or similar article showing my new design.

The half of the collar shown in dot-and-dash lines is identical with the half shown in detail.

I claim:

The ornamental design for an embroidered collar or similar article, as shown and described.

AUGUST RUESCH.
